LINE HOLDER FOR WINCHES

Gerald R. Hunt, Long Beach, Calif.

Application October 25, 1948, Serial No. 56,401

5 Claims. (Cl. 254—190)

1

This invention is concerned with a line holder for winches, or the like, and it is an object of the invention to provide a simple, effective, easily operated device acting on or in connection with a winch or line handling drum to hold the line coiled snugly on the drum even though its extending or working portion may be free so as to be loose.

Winches or hoists of various kinds are employed for various services and it is common to use wire lines on the drums of such devices which lines wrap or coil satisfactorily and remain coiled so long as tension is maintained on the line. However, when the working end of the line is loosened or released the line tends to free itself from the drum, with the result that it may kink or tangle or requires manipulation before the structure is operated.

It is a general object of this invention to provide a device operating on or in connection with a winch or hoisting drum so as to maintain pressure on the line where it is wound on the drum so that undesirable looseness of the line does not occur or develop. With the device of the present invention operating on a line wound on a drum the line is uniformly maintained in proper coiled condition on the drum so that the line does not become criss-crossed, loose, tangled, or so disposed as to require manipulation preliminary to operating the drum.

Another object of this invention is to provide a structure applicable to a winch either directly thereto or to a fixed part adjacent thereto, and which includes a line engaging member preferably in the form of a roller which contacts the line on the drum of the winch to maintain it in proper wound condition on the drum.

Another object of this invention is to provide a device of the general character referred to which is of simple sturdy practical construction. The device provided by the present invention provides or involves few simple, inexpensive parts, is easily mounted to properly cooperate with a drum and is entirely free of complicated or delicate parts likely to fail, wear or become inoperative.

It is another object of this invention to provide a device of the general character referred to including a line engaging roller carried by spaced ears projecting from a bracket which roller has a rubber tread with end flanges serving to prevent tangling or fouling of the line with the device in the course of normal handling or operation of the line.

The various objects and features of my inven-

2

tion will be fully understood from the following detailed description of typical preferred forms and applications of the invention, throughout which description reference is made to the accompanying drawings, in which:

Fig. 1 is a perspective view of a typical winch or hoist showing the device embodying the present invention combined with the hoist in a typical manner. Fig. 2 is a detailed transverse sectional view of the structure shown in Fig. 1, showing in detail the manner in which the device of the present invention cooperates with the line carried on the drum. Fig. 3 is a longitudinal detailed sectional view of the roller of the line holding device showing the manner in which the roller is mounted and the manner in which the roller is related to the drum of the hoist. Fig. 4 is an enlarged detailed sectional view taken as indicated by line 4—4 on Fig. 3 and Fig. 5 is an enlarged sectional view similar to a portion of Fig. 3, showing a modified form of construction.

The structure provided by this invention is applicable, generally, to hoists or winches and is shown in the drawings applied to a hoist of typical form commonly employed for general use or service. The type of hoist illustrated may be used in a situation where it is mounted stationary or on a fixed base or foundation, or it may be used to advantage on a truck or other vehicle.

The hoist shown in the drawings involves, generally, a frame 10 having a base formed of parallel beams 11, and spaced standards 12 and 13 on the base carrying a shaft 14 supporting the drum 15 which carries the line 16. A suitable drive mechanism is carried by or in one of the standards, for instance, within standard 13, said mechanism being operated by a back shaft 17. The ends of shaft 14 project beyond or outward of the standards 12 and 13 and are shown equipped with catheads 18. The line 16 is wrapped on the drum 15 to be confined thereon by end flanges 19 and 20 provided at the ends of the drum. In the particular case illustrated the end flange 19 of the hoist drum is extended axially and forms a housing encasing a suitable brake mechanism.

The structure provided by the present invention involves, generally, a line engaging roller A, a roller carrier extending through the roller and projecting from the ends thereof, anti-friction means C supporting the roller on the carrier, a mounting bracket D supporting the carrier, means E pivotally securing the bracket to a stationary support and means F normally yieldingly urging the roller into pressure engagement

55

with the line or with several coils of the line carried on the drum of the hoist.

The line engaging roller A extends parallel with the drum 15 and enters between the flanges 19 and 20 of the drum to simultaneously engage a plurality of turns or coils of the line occurring on the drum, as shown in Figs. 1, 2 and 3 of the drawings. In its preferred form the roller involves a tubular core 25 preferably of metal, and a jacket or tread 26 on the core. The tread is formed of one or more sleeve-like parts formed of rubber or the like. The tread is preferably a body of rubber of substantial thickness and occupies the core 25 from one end to the other. The tread may be uniform in diameter from one end to the other, as shown in Fig. 3, or, as shown in Fig. 5, it may have end flanges 27 which have some effect as line guides but which flatten or deflect on the coils of the line carried on the drum in the manner shown in Fig. 5. From an examination of Fig. 5 it will be seen how the flange 27, when flattened or deflected, extends axially beyond the end of the roller to overlie the end of the supporting bracket D which carries the end of the roller.

The carrier B is preferably a simple straight rod extending through the roller and projecting somewhat from the ends thereof and in the preferred form of the invention illustrated in the drawings the carrier rod is polygonal in cross sectional configuration and its ends are tightly carried in the ears of the bracket D.

The anti-friction means C supporting the roller on the carrier preferably involves bearings at the ends of the roller and in the form shown the bearings are ball bearings each having an inner race 30, an outer race 31 and a series of balls 32 between the races. In the case illustrated the outer races 31 are pressed or snugly engaged in the ends of the roller core 25 while the inner races are slidably carried on the polygonal carrier B.

The bracket D is preferably a rigid unit or element with spaced projecting ears 40 between which the roller is mounted. The roller carrier B extends between and has its ends tightly engaged in openings provided in the ears 40.

The bracket D in the form illustrated in the drawings involves spaced parallel arms 41 with the ears 40 projecting from them. A web in the form of a plate 42 extends between and braces the arms 41 maintaining them in parallel relationship as shown in the drawings. In the case illustrated a stiffening rib 43 is joined to one edge of the web 42 and extends between the arms 41 and serves to effectively stiffen the entire bracket.

The means E pivotally securing the bracket D to a suitable base or support serves to pivotally connect the bracket to any suitable element or part fixed relative to the drum of the hoist. If the hoist is on a vehicle the means E may be secured to a part of the vehicle which is stationary relative to the hoist. However, in the drawings I have shown units of means E securing the bracket D to the beam members 11 of the hoist frame 10.

Each unit of the means E involves a lug 50 projecting from an arm 41 of the bracket D, a lug 51 projecting from a foot 52 and a pivot pin 53 connecting the lugs 50 and 51. The feet 52 of the means E may be secured to the fixed part as for instance to the beam 11 of the hoist frame drawings.

by suitable fasteners 55 such as are shown in the drawings. The means F normally yieldingly urging the

D to a part fixed relative to the drum so that the roller A is parallel with the drum 15 and is positioned so that it may enter between the flanges of the drum as shown throughout the drawings.

The means F normally yieldingly urging the roller into pressure engagement with the coils of line occurring on the hoist drum preferably involves a tension spring 60 or the like acting on the roller A through the bracket D. In the case illustrated I show a helical tension spring 60 having one end anchored to the frame of the hoist at 61 while the other end of the spring is secured to a turnbuckle 62 which connects the spring with the bracket D. By suitably adjusting the turnbuckle 62 the desired spring tension is applied to the bracket D holding the roller A in pressure engagement with the coils of line occurring on the drum 15.

The structure provided by the present invention is applied to or combined with a hoist so that the roller A is parallel with the host drum and is between the flanges thereof. The means F normally yieldingly urges the roller into pressure engagement with the coils of line occurring on the drum. As the drum of the host is operated either to play the line out or reel it in, the roller rotates and maintains pressure engagement with the coils of line on the drum and as the line is thus operated it may wind into layers on the drum in the usual manner, and as shown in the drawings. With the roller A in pressure engagement with the line on the drum the end portion of the line extending from the drum may be relaxed or released at any time, allowing it to have looseness or play or even to be free without any danger whatsoever of the coils of line on the drum springing loose or becoming somewhat unwound in a manner to cause fouling or tangling of the line. By reason of the line being maintained in snugly coiled condition on the drum the drum is always ready for operation and any danger of fouling or slippage or injury to the like, such as occurs when the line is uncontrolled, is completely eliminated.

Having described only typical preferred forms and applications of my invention, I do not wish to be limited or restricted to the specific details herein set forth, but wish to reserve to myself any variations or modifications that may appear to those skilled in the art and fall within the scope of the following claims.

Having described my invention, I claim:

1. In combination, a drum having end flanges and a line wound thereon between the flanges, a roller engageable between the flanges, a mounting supporting the roller parallel with the drum and between the flanges thereof, and means normally yieldingly holding the roller in pressure engagement with the line on the drum, the ends of the roller being adjacent the flanges on the drum and having yielding flanges thereon.

2. In combination, a drum having end flanges and a line wound thereon between the flanges, a roller engageable between the flanges, a mounting supporting the roller parallel with the drum and between the flanges thereof, and means normally yieldingly holding the roller in pressure engagement with the line on the drum, the roller having a cylindrical line engaging tread formed of rubber and having radially projecting end flanges of rubber at each end of the cylindrical tread.

3. In combination, a drum having end flanges and a line wound thereon between the flanges, a

roller engageable between the flanges, a mounting supporting the roller parallel with the drum and between the flanges thereof, and means normally yieldingly holding the roller in pressure engagement with the line on the drum, the roller having a rubber tread with end flanges and having a tubular core supporting the tread and anti-friction bearings supporting the core.

4. An attachment for a hoist having spaced parallel base beams supporting standards and a line carrying drum rotatably mounted between the standards including, a roller engageable with the line on the drum, a rigid elongate bracket supporting the roller for free rotation, means pivotally mounting the bracket on one beam to project upward therefrom tangential of the drum to a position where the roller engages the line on the drum, and means normally yieldingly urging the bracket to a positioning where the roller is in pressure engagement with the line including, a tension spring arranged beneath the drum with one end connected to the bracket, and means attaching the other end of the spring to the other beam.

5. An attachment for a hoist having spaced parallel base beams supporting standards and a line carrying drum rotatably mounted between the standards including, a roller engageable with

10
15

the line on the drum, a rigid elongate bracket having the roller rotatably mounted at one end thereof, means pivotally mounting the bracket on one beam to project upwardly therefrom tangential of the drum to a position where the frame carries the roller in engagement with the line, and means normally yieldingly urging the bracket to a position where the roller is in pressure engagement with the line including a unit having a helical tension spring and a turn buckle connected end to end, one end of the unit being attached to the bracket, and means attaching the other end of the unit to the other beam with the unit disposed beneath the drum.
